Primary Examiner — Sheryl Lane*Assistant Examiner* — Calvin E Vansant(74) *Attorney, Agent, or Firm* — Withers & Keys, LLC(57) **CLAIM**

The ornamental design for a fire pit, as shown and described.

DESCRIPTION

FIG. 1 is a perspective view of a fire pit showing my new design;

FIG. 2 is a frontal view of the fire pit shown in FIG. 1;

FIG. 3 is a rear view of the fire pit shown in FIG. 1;

FIG. 4 is a side view thereof as viewed from the right-hand side of the fire pit shown in FIG. 1;

FIG. 5 is a side view thereof as viewed from the left-hand side of the fire pit shown in FIG. 1;

FIG. 6 is a top view thereof; and,

FIG. 7 is a bottom view thereof.

The broken lines shown in the drawings illustrate portions of the fire pit that forms no part of the claimed design.
